(57) CLAIM

The ornamental design for a watercolor paint box, as shown and described.

DESCRIPTION

FIG. 1 is a front, right, and top perspective view of a watercolor paint box, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front, right, and top perspective view of the watercolor paint box of FIG. 1 in a use state. The broken lines shown in the drawings are included for the purpose of illustrating portions of the watercolor paint box that form no part of the claimed design.
